UNITED STATES PATENT OFFICE.

LEON S. BRACH, OF EAST ORANGE, NEW JERSEY, ASSIGNOR TO L. S. BRACH MANUFACTURING CO., OF NEWARK, NEW JERSEY, A CORPORATION OF NEW JERSEY.

DESIGN FOR AN INSULATOR.

Application filed March 5, 1925. Serial No. 12,608. Term of patent 7 years.

To all whom it may concern:

Be it known that I, LEON S. BRACH, a citizen of the United States, residing at East Orange, in the county of Essex, State of New Jersey, have invented a new, original, and ornamental Design for an Insulator, of which the following is a description, reference being had to the accompanying drawing and to the figures of reference marked thereon.

Figure 1 is a view in elevation of the insulator.

Figure 2 is a view similar to Fig. 1, but at right angles thereto.

Figure 3 is a plan view of Fig. 1, all showing my new design of an insulator.

I claim:

The ornamental design for a insulator as shown.

In testimony whereof, I affix my signature.

LEON S. BRACH.
